Henry McElish of Walpole New Hampshire
Letters Patent

The Schedule referred to in their Letters Patent and making part of the same containing a description in the words of the said Henry McElish him self of his improvement being a machine for turning Laths, Boat ^{spokes} and other articles that may be turned by a pattern.

To all to whom these presents shall come. Be it known that I Henry McElish of Walpole, in the County of Cheshire and State of New Hampshire have invented a new and useful improvement in the useful arts being a machine for turning Laths, Boat, spokes, and other articles, that may be turned by a pattern called McElishes pattern guiding turning lathe, and that the following is a full and exact description of the construction and operation of the same as invented as improved by me no reliance being had to the associated drawings.

Fig. 1. is a perspective view of the machine. A B. The frame is constructed by mortising and tenoning together four posts, eight rails, and two cross rails to support the main cylinder, and the rail C to support the gauge post and finisher. The whole being made of timber three inches and a half square and forming a frame three feet & three inches long, and three feet and less inches wide, and two feet and seven inches high. The rail B being the whole thickness above the rest of the frame. C. is a carriage running on tracks in the top end rails of the frame, and is three feet seven inches long, by two feet seven inches wide. The inside corners of the long rails of this carriage are halved away as to form a ledge for the carriage D to slide on. D is a carriage containing the cylinder, and dogs, and gears, to hold and turn the pattern and timber to be worked. The width of this carriage is such as to fit into the carriage C in which it slides. The length one foot nine inches and one half, and the height one foot two inches. The rails are made of lumber three inches square being framed together and made fast at the end D with bolts, the side rails having one half their thickness cut away at the under side to within six inches of the top rail.

at the end D (see see Fig. 20) when they are represented with long openings, through which bolts are passed to make them fast to the sill B. into this sill are framed two head blocks, to receive the centre or rank C. at a distance of one foot four inches apart. D. d. are two pieces of board dove-tailed into the tops of the head blocks in the sill B. and reaching to the opposite end of the carriage where they are made fast with bolts passing up through the cap piece D. and the long narrow openings in them. This cap piece is supported by six standards dove-tailed into the sill below and the cap piece. Throw on either side opposite to each other they being three inches wide and one inch thick. The two outside pairs standing at such distance apart, as to receive the arbors and gears, E. f. with dogs at the ends, at a distance of one foot and four inches apart and the other pair midway between them where the gear and feeding screw is placed. These gears being two inches in diameter, and each having thirteen cog or teeth. H is a shaft of iron with end slips, screws attached to it to work into the gears above described. E. f. turning above and g. below the shaft which is supported at each end by pieces running across and connecting the standards C. and f. to their mates i. is a pinion of iron, five inches long and two in diameter the arbor of which is attached to the shaft H. by drilling a hole in the end of the shaft and inserting an oval head on the end of the pinion arbor and passing a pin through both. The pin hole in the shaft should be oblong, so as to let the pin and head play in the end of the shaft. This pinion is placed under and works into the long end slips, screw J. which is attached to the end of the same arbor in the same manner as the shaft and arbor above described. K is a perpendicular piece one inch thick, attached to the cap piece D of the carriage at the aper end, the cap piece extending eleven inches from the standard C. and attached at the other end to another piece one inch thick made fast to the sill and extending a like distance from the standard C. L is a movable piece supporting the pinion which may be raised so as to bring the pinion into gear with the arbor by depressing the end of the lever M which it is kept by operation of a spring at the lower end of the lever M. and

the point the top of it which is thrown into the movable frame as it is raised. D is a two inch circular saw with two hooks or cutters one eighth of an inch thick attached to it, they being three fourths of an inch wide and reaching from the back to within one fourth of an inch of the edge of the saw, each having a spur at the edge and made fast to the saw, by passing screws through it into them. (See Fig. III.) E is the pulley on the saw above, the arbors and spur are supported by the three head blocks, & the centre one being one inch thick, the others three. S is a post forced into the cross rail & and supports a vertical bearing gauge made of steel and bent to a curve to correspond with the circle of the saw, and turns on bearings at the ends, (See S. t. Fig IV.) F is the finisher's square being had to the anvise drawing Fig IV. (a sectional view) it is a circular plate or file seven inches in diameter and half an inch thick, rounded round at the periphery to the curve of a quarter of a circle, and turns on arbor in the standard V and a corresponding one opposite to it which are made fast to the sills W. with bolts. The sills two feet long, two and a half inches wide, and one inch thick and standing three and a half inches apart, being connected at the end W. by a piece one inch thick and four wide X is a gauge wheel of metal of the same dimensions of the circular file above described, but smooth at the periphery, and supported in the same manner except the standards are soldered at the bottom and the sills made fast with bolts passing through from side to side. The centre of the file and gauge wheel standing one foot four inches apart. It is a cap piece with a groove in the under side into which a tenon at the top of the gauge standard is fitted also a tenon at the top of the piece Z. This piece being made fast to the back rail of the carriage C. G is a hook attached to the finisher which when drawn back passes thro' the piece Z. where it may be made fast by turning the button H on the back side of it. The sills of the finisher running tracks on each side of the rail & I is a cord attached to the finisher passing over a pulley in the rail & and a weight attached to it to keep the gauge wheel against the pattern. K is a cleat with a point at the lower end and a spring catch at the top.

with a hole and thread between the two parts to receive the feeding screw *q*. This clamp being mounted in the head block *C*. To keep the carriage bearing so as to keep the pattern in contact with the quage *t* a spiral spring is attached at one end to the back rail of the carriage *C*. The other end to the rail *B*. The operation is as follows. any of the power usually made use of to propel machinery is applied by a belt on the pulley *I*, and a belt from the main cylinder over the pulley *P* and a round band over a pulley on the first arbor which puts the saw and finisher in motion. The timber to be turned should be suspended by the ends between the dog on the arbor *C*. and the centre *C*. and between the saw and file. The pattern in the same manner by the other dog and centre between the two quages. Then by liberating the carriage *C* from the back rail of the frame by turning a button the spiral spring will move it toward saw, and the pattern against the quage *t*. The carriage *D* being previously moved to the end *c* of the other carriage and the clamp *p* shut on to the feeding screw then by depressing the end of the lever *m*. The pinion *i* will be geared into the screw *J* and give motion to timber pattern and carriage after saw and hooks have cut a sufficient number of times round the timber the button *EE* should be turned and the finisher let up to timber, when the carriage *D* has passed to the opposite end of the carriage *C*. The lower end of the lever *m* will come in contact with a pin across the lower end of the head block *y*. and the pinion *i* will drop, when the motion of the carriage will stop so that they may be drawn back and the work taken out. The Invention here claimed and for which a patent is desired to be secured is, first the combined application of the saw and hooks, and some attached to their arbors. 2° the application of gears to the arbors, to which the dogs are attached for the purpose of turning the timber and pattern. 3° the application of the circular file for finishing. The above described combination being necessary to effect the required operation. The size and proportions of the whole may be varied to suit the uses and purposes of the constructor.
